UNITED STATES PATENT OFFICE.

WILLIAM D. ANTRIM AND REINHOLD FEHRENBACH, OF GLOUCESTER, NEW JERSEY,
ASSIGNORS TO WELSBACH COMPANY, OF GLOUCESTER, NEW JERSEY, A CORPOR-
ATION OF NEW JERSEY.

DESIGN FOR A HEATER.

Application filed May 11, 1921. Serial No. 468,744. Term of patent 14 years.

To all whom it may concern:

Be it known that we, WILLIAM D. ANTRIM and REINHOLD FEHRENBACH, both citizens of the United States, residing at Gloucester, in the county of Camden and State of New Jersey, have invented a new, original, and ornamental Design for Heaters, of which the following is a specification, reference being had to the accompanying drawings, forming part thereof, in which—

Figure 1 is a perspective view of the heater, and

Figure 2 is a plan view of the base.

We claim:

The ornamental design for a heater, as shown.

In testimony whereof, we have hereunto set our hands.

WILLIAM D. ANTRIM.
REINHOLD FEHRENBACH.
